HYDRAULIC PRESS

James Maynard, Los Angeles, Calif., assignor to
Frank R. Galbreath, Los Angeles, Calif.

Application December 9, 1937, Serial No. 178,964

3 Claims. (Cl. 103—37)

My invention relates to hydraulic presses. An important object of the invention is to provide in a hydraulic press driven by a constant speed motor, mechanism for progressively decreasing the speed of the pressing jaws in direct proportion with the increase of pressure required.

Other objects are to provide means in a hydraulic press whereby the prime mover, though continuously operating at a constant speed, may maintain pressure on the pressing jaws substantially constant, may decrease the pressure slowly or rapidly, or may increase the pressure at a speed in inverse proportion to the increase in the pressure requirement at the work station.

15 A further object in a hydraulic press is to provide mechanism whereby the pump piston or pistons always draw in their maximum amount of liquid on the suction stroke, irrespective of the power requirement, and the provision of means to utilize varying amounts of the pressure liquid on the power stroke of the pistons, depending upon the pressure requirements of the press.

20 The invention also comprises novel details of construction and novel combinations and arrangements of parts, which will more fully appear in the course of the following description.

In the drawings, like reference characters designate similar parts in the several views.

25 Figure 1 is a plan view, partly broken away, showing an embodiment of my invention.

Figure 2 is a side elevation of said embodiment, showing in section a tank comprised in the invention.

30 Figure 3 is a broken, enlarged view of the principal actuating mechanism, as shown in Figure 2.

Figure 4 is an enlarged vertical section taken on the line 4—4 of Figure 1, looking in the direction of the arrows.

35 Figure 5 is a section taken on the line 5—5, looking in the direction of the arrows.

Figure 6 is an enlarged section taken on the line 6—6 of Figure 3.

Figure 7 is a broken section taken on the line 7—7 of Figure 1.

40 Referring more in detail to the drawings, the reference numeral 6 designates generally a frame having a relatively fixed jaw 7 and relatively movable pressing jaw 8. The movable jaw 8 is slidable on a track 9 on the frame 6.

A helical spring 10 abuts, and thereby resists pressing movements of, the movable jaw 8. A rod 12 in the spring prevents the latter from buckling.

45 To actuate the movable jaw 8, a piston 13 is

provided in a cylinder 14. A piston rod 15 connects the piston with the movable jaw 8.

The prime mover of the mechanism is an electric motor 16 having a vertical drive shaft 17 mounted in a bearing block 18. The lower portion of the shaft 17 is provided with crank arms 19.

45 A double faced, rotary cam 21 is mounted on the shaft 17 between a bearing 20 and the motor 16. One face of the cam faces upward and the other downward. The cam faces are reversed with respect to each other, but otherwise similar. Each face comprises a depressed plane 22, a raised plane 23 and an incline 24 leading from one plane to the other.

50 Riding on the upper cam face is a roller 25, while a roller 26 rides on the lower cam face. The rollers 25 and 26 are respectively carried by cranks 27 and 28. The shape of these cranks is perhaps best shown in connection with crank 27 in Figure 5. Cranks 27 and 28 are respectively pinned at one end of each of the rods 29 and 30.

55 Sleeves 31 and 32 are respectively pinned to the opposite ends of the rods 29 and 30. The sleeves 31 and 32 have squared female openings 33. The sleeves 31 and 32 are thereby slidable on squared ends of bars 34 and 35 respectively. The bars 34 and 35 are otherwise cylindrical, whereby they may be mounted in a double bearing 36 for rotation.

60 Crank arms 37 and 38 are on projecting ends of the bars 34 and 35 respectively. Tappet rods 39 and 40 connect with fingers 41 and 42 through the intermediary of cranks 43 and 44 on the ends of spindles 45 and 46 respectively. The fingers 41 and 42 are mounted on a valve housing 47 by means of the spindles 45 and 46. The fingers 41 and 42 respectively maintain intake valves 48 and 49 away from their seats in the valve housing 47. Light springs 50 are disposed behind the intake valves. A common intake 51 in the housing 47 provides an inlet for liquid.

65 The housing 47 has bores 52 and 53 aligned with the bores of twin cylinders 54 and 55. Pistons 56 and 57 reciprocate in the cylinders 54 and 55 respectively. Connecting rods 58 and 59 connect the pistons 56 and 57 with the crank arms 19 of the crank shaft 17.

70 The discharge ends of the bores 52 and 53, within the housing 47, are connected with passages 60 and 61 respectively. Check valves 62 and 63 prevent retrograde movement of liquid back into the passages 60 and 61 from a main or common passage 64. Light springs 65 are arranged behind the check valves 62, 63.

Passage 64 has two branches 66 and 67. Fluid discharging through the outlet 68 of the branch 66 empties into a bore 69 leading to the interior of the press cylinder 14.

- 5 The mechanism is largely submerged in a body of oil 70 in a tank 71. By reason of the connections hereinbefore explained, liquid is being pumped into the passage 64 whenever the motor 16 is operating. When it is desired not to actuate the pressing jaw, the liquid in the passage 64 is by-passed back into the body of oil 70, by means of the branch 67.
- 10 10 The valve 72 controls the discharge from the branch conduit 67. A replaceable seat 73 is provided for the valve 72. When the valve 72 is open, liquid flows from the conduit 67 to the discharge spout 74 back into the body of oil.

15 The valve 72 is controlled by a hand wheel 75, which operates bevel gears 76, 77. The bevel gear 20 76 is keyed to a tubular shank 78 of the valve 72. The shank 78 is threaded to engage interior threads 79 in a bushing 80. Thus by rotation of the bevel gears the shank 78 is raised and lowered and the valve 72 is opened and closed.

- 25 25 The valve 72 is a combined control valve and relief valve. The valve 72 is tubular. A plunger 81 controls the passage through the valve 72. A collar 82 on the plunger 81 is engaged by a coiled spring 83 in the tubular shank 78. A threaded head 84 is disposed to compress the spring 83, to vary the pressure necessary to open the relief valve 81. A stem 85 on the head 84 may be rotated by a hand wheel or suitable tool. An outlet 86 through the wall of the tubular valve 72 permits discharge of excess pressure liquid when the relief valve is opened.

30 30 As the pressure builds up in the cylinder 14, a portion of it escapes into a passage 87. An upwardly directed conduit 88 in a casting 89, connects the passage 87 with a relatively small cylinder 90 for a plunger 91. The plunger 91 carries a floating carrier 92. An upwardly projecting yoke 93 spans the squared portion of the bar 34. Collars 94 are mounted on the bar 34 at either 35 45 side of the yoke 93, to communicate movement of the floating carrier 92 to the cam roller 25, through the intermediary of the sleeve 31, rod 29 and crank 27.

- 40 40 A downwardly projecting yoke 95 spans the squared portion of the bar 35. Collars 96 are mounted on the bar 35 at either side of the yoke 95, to communicate movement of the floating carrier 92 to cam roller 26, through the intermediary of the sleeve 32, the rod 30 and the crank 55 55 28.

50 50 Laterally the carrier 92 has bifurcated lugs 97 and 98, the bifurcations of which receive and slide on plates 99 and 100, which plates are bolted to side members 101 and 102 on the frame. A coiled spring 103 opposes movement of the carrier 92 to the right in Figure 3. The spring 103 is contained in telescoping tubes 104 and 105. A head 106 on the tube 105 has a threaded connection 107 with a stationary abutment 108 also on the frame of the apparatus. By means of this threaded connection, the tension on the spring 103 may be adjusted.

- 60 60 Strengthening ribs for the pressing jaws are provided as suggested at 109. Furthermore, between the motor 16 and the shaft 17, I preferably arrange epicyclic gearing to get a fly wheel effect. Since the details of such gearing are not per se part of the present invention, it is believed that 70 75 76 illustration and detailed description of same are

unnecessary. The housing for such gearing is shown at 110.

The operation of my hereinbefore described hydraulic press is as follows:

After starting the motor 16, the operation of 5 the movable jaw 8 is controlled manually by means of the hand wheel 75. It is of course understood that the relief valve 81 is adjusted to blow off at a desired pressure. The hand wheel 75 controls the valve 72. The latter valve determines whether all the flow, or which portion of the flow, from the cylinders 54, 55 returns to the body of liquid 70 without actuating the press.

Assume first that the valve 72 is closed. Of course, the pistons 56, 57 are being driven by 15 means of the crank shaft 17. On the power stroke of the pistons 56, 57, the flow from the cylinders 54, 55 is discharged into passages 60, 61, and since the check valves 48, 49 are closed on the power strokes, the liquid pumped into the 20 25 passages 60, 61 thereby discharges through the passages 64, 66 and through outlet 68 to the bore 69 leading into the press cylinder 14.

The pressure in the cylinder 14 actuates the piston 13, moving the movable jaw 8 toward the 25 fixed jaw 7.

On the suction strokes of the pistons, the check valves 48, 49 are moved from their seats, permitting measured quantities of oil to be drawn from the reservoir 74 through the inlet 51 and 30 into the cylinders 54, 55. It is of course understood the pistons 56, 57 are connected with opposite throws of the crank shaft, so that one is discharging while the other is drawing in a new supply.

35 It is also to be understood that one cylinder or more than two cylinders, may also be employed, since the principle would be unchanged.

Rotation of the shaft 17 also effects rotation of the cam 21. As the pressure builds up in the 40 main cylinder 14, some pressure escapes through the passage 87, through conduit 88 and into cylinder 90 behind the plunger 91. As the pressure in the small cylinder 90 builds up, the rollers 25 and 26 are fed laterally across the rotating cam 45 50 from the circumference toward the center, by means of the floating carrier 92, rods 29, and 30 and the cranks 27 and 28.

The cam rotates in the direction of the arrow in Figure 5. This figure shows the position of 50 the roller 25 at the start of the intake stroke of the lower piston 57. After the valve 48 has been opened by the beginning of the suction stroke of the piston 57 (or simultaneously with such opening of the valve 48), the incline 24 of the upper 55 face of the cam raises the roller 25 from the depressed plane 22 to the raised plane 23, thus rocking the crank 27. This rocking motion rotates the sleeve 31 and the squared bar 34, by means of their angular fit. Rotation of the bar 34 60 effects rocking of the arm 37, which rocks the finger 41, through the intermediary of the tappet rod 39. The finger 41 then bears against the valve 48, maintaining said valve in an open 65 position.

When the edge 23a of the raised plane of the cam reaches the roller 25, the roller drops down to the depressed plane 22 of the cam face, thus rocking the crank 27 back to its original position and allowing the valve 48 to be closed, by a reversal of the movement of the operating parts between the roller 25 and the valve 48, described in the previous paragraph.

70 75 76 It will be noted that due to the snail shape of the drop-off edge 23a, as the roller 25 is moved

closer toward the center of the cam, the valve 48 is being held open during a progressively longer interval. Thus instead of pumping the maximum load of the cylinders 54, 55 at each 5 stroke of the piston, as the pressure requirement at the work station increases, more and more of the liquid in the cylinders 54 and 55 is pumped back into the reservoir 71 past the valve 48, which is being held open by the finger 41.

10 The operation of the valve 49, its actuating roller 26 and the intermediary mechanism is similar to that just described in connection with valve 48, roller 25 and associated mechanism, except that they operate at diametrically opposite 15 points in the cycle of operation of the machine.

The valves 62, 63 act as check valves to prevent retrograde movement of liquid in the passage 64.

Thus it will be noted that preferably (though not essentially) the fingers 41, 42 are not employed to open the valves 48, 49, but merely to maintain the valves open, thus permitting a 20 lighter construction.

Moreover, by holding said valves open progressively longer periods as the pressure requirement at the work station increases, the speed of movement of the movable jaw is automatically and proportionately reduced even though the motor 16 is operating at a constant speed. By using relatively smaller portions of the discharge 30 of the pumps, as the pressure requirement increases, the horsepower of the motor does not have to be increased. By propelling the movable jaw forward slower as the pressure increases, proportionately faster speeds are obtained as 35 the pressure is proportionately less. Thus a motor of less horsepower may be used as the prime mover, without sacrificing power at high pressures or speed at lower pressures.

Another advantage of the present construction 40 is that the cylinders 52, 53 are filled on each suction stroke, irrespective of the pressure encountered. This mode of operation makes measurement of the amount discharged more accurate, by eliminating air pockets in the liquid.

45 Still another advantage of the present invention is that pressure of the pressure jaws may be maintained constant by opening the valve 72 just sufficient to balance the amount being pumped into the passage 64 by the pistons. The additional amount that the valve 72 is then opened will determine the speed of recession of the jaw 8, or partially closing the valve 72 will cause the jaw 8 to move forward at a reduced rate of speed. Thus the speed of applying pressure, the speed of 50 reducing the pressure, or the maintaining of a certain pressure may be regulated by the hand wheel 75 operating the valve 72.

As increasing pressures are applied to compress the spring 10, the tension of the spring thus increases, which tends to balance the pressure against the movable jaw at the working point. The spring 103 of course tends to move the rollers 25, 26 toward the periphery of the cam. The springs 50, 65 tend to seat the ball valves in the 55 housing 47.

While I have illustrated and described what I now regard as the preferred embodiment of my invention, the construction is, of course, subject to modifications without departing from the

spirit of my invention. I, therefore, do not wish to restrict myself to the particular form of construction illustrated and described, but desire to avail myself of all modifications which may fall within the scope of the appended claims. 5

Having thus described my invention, what I claim and desire to secure by Letters Patent is:

1. A variable delivery pump for the hydraulic operation of presses and the like including a plunger of constant, uniform stroke and a pressure feed line leading therefrom and provided with a branch conduit, a constantly rotated shaft having operative connection with said plunger for actuating the same, a cam constantly rotating with said shaft and presenting a variable cam surface, valves effective in the intake of fluid to said pump and its discharge into said feed line, means engaging certain of said valves for rendering the same ineffective during a portion of the pump operation, a take-off in adjustable engagement with the variable surface of said cam, controlling the duration of effectiveness of said valve engaging means, and including relatively movable parts shiftable to adjust the take-off relative to the cam, and a plunger actuated by pressure from said branch conduit for shifting certain of said parts of the take-off relative to the other and to said cam. 15

2. A variable delivery pump having an intake valve and an outlet valve, and a pressure line controlled by the outlet valve and having a branch conduit leading therefrom, a plunger having a constant stroke therein, a constantly rotating shaft having means actuating said plunger, a cam mounted on, and rotating constantly with, said shaft and presenting a variable cam surface, a rocker arm having a free end engaging the intake valve and movable to hold the said valve from seating during a selected period of operation of the pump, a rock shaft in sections one of which 30 is axially movable and adjustably in engagement with said cam surface and the other of which is operatively connected to the said rocker arm, and a plunger actuated by pressure from said branch conduit and connected to said adjustable 35 section of the rock shaft for moving the latter to control its effective relation with the cam. 40

3. A variable delivery pump for the hydraulic operation of presses and the like including a plunger of constant, uniform stroke and a pressure feed line leading therefrom and provided with a branch conduit, a constantly rotated shaft having operative connection with said plunger for actuating the same, a cam on said shaft and constantly rotating therewith and having two 50 planes and a snail-shaped drop-off from one plane to the other, a valve to bleed pressure from the pump, a take-off adjustably in contact with the cam and in operative connection with the said valve to hold the latter open when on the upper plane of the cam, and a plunger actuated by pressure from said branch conduit for adjusting the take-off in respect to the cam to control the drop-off thereof from one cam plane to the other and thus vary the duration of opening of the bleed valve in proportion to pressure in the pressure line. 55 60 65

JAMES MAYNARD.
